UNITED STATES PATENT OFFICE.

FREDERICK J. BEHNEMAN, OF SAN FRANCISCO, AND HAROLD S. REXWORTHY, OF SUNNYVALE, CALIFORNIA.

ROD MILL.

1,414,768.

Specification of Letters Patent. Patented May 2, 1922.

Application filed November 7, 1921. Serial No. 513,470.

To all whom it may concern:

Be it known that we, FREDERICK J. BEHNEMAN, citizen of the United States, and HAROLD S. REXWORTHY, subject of Great Britain, 5 residing the said BEHNEMAN in the city and county of San Francisco and State of California, and said REXWORTHY, of Sunnyvale, county of Santa Clara, State of California, have invented certain new and useful 10 improvements in Rod Mills, of which the following is a specification.

The present invention relates to an improvement in a classifying apparatus, particularly that type illustrated in Letters Patent No. 1,142,159, dated June 8, 1915.

The present invention has for its principal objects to provide a mill or crushing apparatus having a central feed whereby the end discharge in either direction is provided with the material acted on travelling in the same distance from the central feed to the discharge at either end. A further object is to provide a classifying rod mill with a crushing anvil in a position to receive 20 the material to be crushed as delivered into the mill; to provide a receiving zone between opposite sides of the anvil to the material discharge, whereby the partly crushed material is distributed over the entire circumference of the mill for recrushing; and 30 to provide a construction which with slight change is adapted for use as a wet or dry mill.

The invention consists broadly in a rotatably mounted tubular shaft affording a material feed from opposite ends toward its center and which shaft mounts or provides an axis of rotation for a cylinder or shell divided into a plurality of radial communicating compartments, within each of which is contained a group of independent crushing rods held within the cylinder by end walls formed with outlet openings for the escape of the crushed material after the 40 same passes from a crushing anvil or from between the rods through a receiving zone adjacent to the discharge openings.

With the above mentioned and other objects in view, the invention consists in the 50 novel construction and combination of parts hereinafter described, illustrated in the accompanying drawings and pointed out in the claims hereto appended; it being understood that various changes in the form, proportion, size and minor details of construc-

tion within the scope of the claims may be resorted to without departing from the spirit or sacrificing any of the advantages of the invention.

To more fully comprehend the invention, 60 reference is directed to the accompanying drawings, wherein—

Fig. 1 is a broken longitudinal sectional view of the preferred form of our apparatus.

Fig. 2 is a vertical transverse sectional 65 view taken on line 2—2 of Fig. 1.

Fig. 3 is a vertical sectional view through the receiving zone at one end of the shell, taken on line 3—3 of Fig. 1.

Fig. 4 is a modified form of the receiving 70 zone employed when the apparatus is used as a dry mill.

In the drawings of the apparatus, wherein the same is illustrated as a wet mill, and wherein like characters of reference designate 75 corresponding parts in the several views, the numerals 1 indicate parallel spaced supporting posts or standards, each mounting a bearing 2 of any suitable or conventional form, within which are journaled 80 the opposite ends 3 of a tubular mill supporting shaft 4, formed at its opposite ends with the material feed openings 5, and in its center with the spaced openings 8. On each end of the shaft is mounted to rotate there- 85 with a well known form of feed head 9 having an inlet opening 10 adapted on each revolution of the shaft to dip into a material containing trough 11 and remove therefrom a quantity of material. In the drawings, but 90 one of the heads 9 is illustrated.

The interior of the shaft 4 is formed with a feed worm 12 at each end for conveying the ore or material to be crushed from opposite ends of the tubular shaft inwardly toward 95 the central discharge openings 8. The shaft 4 at a point adjacent the openings 8 is formed with an annular hub 13 longitudinally grooved on its periphery between said openings 8, as at 14, to receive the inner 100 ends 15 of the radially disposed plates 16, of a width corresponding to that of the hub 13. The plates 16 at their outer ends are received in grooves or channels 17 formed on the inner face of an annular anvil ring 105 18 formed with outwardly diverging or bevelled side walls 19, a main rib 20 and transverse webs 21 at either side of said main rib and connecting the same with said walls 19. The inner face or surface of the anvil 110

ring 18 is lined with an anvil surface or face 22, bolted thereto as at 23, with the ends of each section of said surface receivable in grooves or channels 24 at opposite sides of the outer ends of said members 16.

It will be apparent that this construction provides a plurality of quadrant shaped chambers 29' surrounding the shaft 4, each communicating with the interior of the shaft 4 through one of said openings 8.

The main rib 20 of the anvil ring 18 carries a rack 25 intermeshing with a driving pinion 26 adapted for imparting rotation to the ring 18 and shaft 4.

On each side of the hub 13 the shaft 4 is mounted a suitable shell supporting ring 27 formed with apertures 28 registering with the quadrant shaped chambers 29', heretofore described.

Mounted to rotate with the shaft 4 and positioned one at the outer side of each ring 27, are the cylinder end plates 29, with each of which is connected through a securing ring 30 bolted thereto, as at 31, the outer end or edge of a shell or plate 32, each suitably secured as at 33 to one of the bevelled side walls 19 of the anvil ring 18. The shells 32 are conical in form with their smallest diameter connected with the rings 30, providing an annular pocket or receiving zone 34 intermediate the opposite sides of the anvil ring and the respective cylinder end members 29.

The construction described provides a plurality of radial quadrant shaped chambers 29' about the shaft 4, near its center, and which chambers all communicate at either side of said anvil ring between its opposite edges and the end plates 29, particularly within the sphere of the receiving zones 34.

The rings 27 on their periphery are provided with ears 35 disposed radially therefrom and each is secured to a baffle plate 36 in contact at one edge with the bevelled side wall 19 of the anvil ring 18 and with the inner surface of the shell 32, and terminating near the inner face of the end plate 29. Each end plate is provided, as in Fig. 2, with a rod hole, closed by a plate 37, and a manhole closed by a plate 38, and also with an annular series of gratings 39, adjacent its periphery, affording outlet openings for the discharge of the crushed material from the cylinder, each of said openings being covered by a suitable screen 40. Each end plate is also provided with an outwardly curved or flaring discharge lip 41 disposed circumferentially of the gratings 39 and screens 40.

Within each quadrant shaped compartment or chamber 29' is positioned a group of independent crushing rods 42, preferably cylindrical in end elevation and of a length to loosely abut against the inner faces of the end walls 29, said group of crushing rods on the rotation of the cylinder rolling on each

other and on the relatively wide crushing surface formed with the faces of the members 16 and 22 and a portion of the hub 13.

It will be observed that the material fed inwardly from opposite ends of the shaft 4 discharges through openings 8 into the quadrant shaped or segmental chambers 29' surrounding the hub 13 and onto the crushing rods 42 at a point immediately above and within the sphere of the anvil surface 22, affording a maximum crushing area within each compartment for the material immediately on its delivery thereinto. The rotation of the cylinder enables the group of crushing rods 42 to act on the material as the same passes from the anvil toward the discharge gratings 39, as on each revolution the material contained within the receiving zone 34 is picked up or raised by the plates 36 and dropped downwardly into said groups of crushing rods 42, which in their action further crush the material and which crushed material drops therefrom or from therebetween into the receiving zone 34, the larger particles settling to the bottom and the lighter particles or finely crushed material draining therefrom and passing through the grating 39 and screens 40.

By reference to Fig. 4 it will be observed when the apparatus is used as a dry mill, the cylindrical shell 32 is outwardly flared from its inner to its outer edges in the form of a shell 42, just the reverse of the form illustrated in Fig. 1, this construction permitting the ready passage of the dried crushed material from opposite sides of the anvil into and through the discharge openings formed by gratings 39 and screens 40. If desired, suitable guards 43 may be positioned over the opposite ends 29 to arrest the material which may be thrown by centrifugal action from the discharge lips 41.

Under certain conditions it has been found desirable, particularly when the material to be treated contains considerable dust or fine particles, to provide in the surface of the tubular shaft 4, at the inner end of the feed worm 12, one or more annular series of slots or dust passages through which the very fine material which needs but little pulverization may pass directly onto the crushing rods above the receiving chamber 34.

Having thus described our invention, what we claim as new and desire to protect by Letters Patent is:

1. An axially rotating crushing apparatus comprising feed means adapted to supply material to the center of said apparatus, a plurality of groups of crushing members arranged annularly about the same and fixed with respect one to the other, means for rotating said groups in unison about the axis of rotation of the apparatus, a shell enclosing said groups, means for introducing material to be crushed to said groups midway

of their length, and a series of outlets for the crushed material at the opposite ends of said shell.

2. A crushing apparatus comprising feed means adapted to supply material to the center of said apparatus, a plurality of groups of crushing members arranged annularly about the same and fixed with respect one to the other, means for rotating said 10 groups in unison about the axis of rotation of the apparatus, a shell enclosing said groups, means for introducing material to be crushed to said groups midway of their length, a series of outlets for the crushed 15 material at the opposite ends of said shell, and an annular series of receiving chambers within said shell adjacent to its opposite ends.

3. A crushing apparatus comprising feed 20 means adapted to supply material to the center of said apparatus, a plurality of groups of crushing members arranged annularly about the same and fixed with respect one to the other, means for rotating said 25 groups in unison about the axis of rotation of the apparatus, a shell enclosing said groups, means for introducing material to be crushed to said groups midway of their length, a series of outlets for the crushed 30 material at the opposite ends of said shell, a crushing anvil associated with each group of crushing members and disposed annularly of the axis of rotation of the apparatus and approximately midway of its length, and 35 an annular series of receiving chambers between the opposite ends of said anvil and the ends of said shell.

4. An axially rotating crushing apparatus comprising feed means adapted to supply 40 material to the center of said apparatus, a cylinder surrounding the same, end plates for closing the cylinder ends, a crushing anvil extending annularly within the cylinder, crushing rods within the cylinder and 45 loosely abutting against said end plates, said end plates each provided with a discharge opening for the crushed material, means for discharging material centrally into said cylinder midway of its length onto said rods at 50 a point contiguous to said anvil, and means for rotating the shaft and cylinder.

5. A crushing apparatus comprising feeding means adapted to supply material to the center of said apparatus, a rotatable cylinder surrounding the same, end plates at 55 the opposite ends of the cylinder, a crushing anvil extending annularly within the cylinder approximately midway of its length, crushing rods within the cylinder 60 and loosely abutting against said end plates, said end plates each provided with a discharge opening for the crushed material, means for feeding material into said cylinder longitudinally of said shaft, and an annular series of receiving pockets at opposite 65

ends of the interior of the cylinder adjacent its opposite ends.

6. A crushing apparatus comprising a plurality of groups of crushing rods arranged 70 annularly about a common axis and fixed with respect one to another, a cylinder enclosing said groups, the rods of said groups being free to move with respect one to another, but constantly assembled en masse, means for rotating said groups in unison 75 about said common axis, means for feeding material to be crushed to the center of said apparatus and for discharging the same onto said groups midway of their operative length and an annular series of material receiving pockets adjacent the ends of said groups of crushing rods and opening to the interior of said cylinder.

7. A crushing apparatus comprising a crushing anvil rotatable on a horizontal axis 85 and provided with apertures, a plurality of groups of crushing rods arranged annularly about said axis of rotation, one group within each aperture whereby said groups are fixed with respect one to another, the rods 90 of said groups being free within their respective apertures to move with respect one to another to constantly assemble en masse, a cylinder enclosing said groups and rotatable therewith, means for feeding 95 material to be crushed to said rods at approximately their longitudinal center and at their point of co-operation with said anvil, and an annular series of products within the opposite ends of the said cylinder 100 adjacent to the ends of said groups of rods.

8. A crushing apparatus comprising a tubular rotatably mounted shaft, an annular crushing anvil rigidly secured thereto and formed with apertures disposed annularly 105 thereof, said shaft provided at one end with a material inlet opening and at a point in register with said anvil with a plurality of material outlet openings communicating with said annular apertures, a plurality of 110 elongated crushing bars within said anvil apertures, and supported midway of their length by said anvil, a shell surrounding said anvil, end plates closing the opposite ends thereof, and against which said crushing bars loosely abut, each of said end plates 115 provided with material discharge openings, means for rotating said shell, and means for feeding material longitudinally of said shaft.

9. A crushing apparatus including a tubular rotating shaft, a crushing anvil carried thereby and provided with apertures disposed annularly of the shaft, said shaft provided with an end feed opening and within 120 its length with a plural series of material discharge openings increasing in size toward the transverse center of said shaft communicating with said apertures, a plurality of elongated crushing bars within each of 125 130

- said apertures disposed longitudinally of the shaft and supported midway of their length by said anvil, a shell surrounding said anvil, end plates closing the opposite 5 ends of said shell and against which said crushing bars loosely abut, each of said end plates formed with a series of annularly disposed outlets, and means for rotating said shell.
- 10 10. A crushing apparatus comprising a cylindrical shell formed with oppositely disposed truncated conical ends, a horizontally disposed rotatably mounted tubular supporting shaft extending axially there- 15 through, said shaft provided with end material inlet and within said shell with a plural series of graduated material discharge feed openings, a plurality of groups of crushing rods disposed parallel with the shaft and 20 freely movable as units within said shell and rotatable as units about the axis of rotation of said shaft, end plates closing the opposite ends of said shell, and against which the rod ends abut, said plates provided with ma- 25 terial discharge openings, a crushing anvil surrounding said shaft at the point of said

material feed openings, and with which said groups of rods co-operate, and means for rotating said shell and shaft.

11. A crushing apparatus comprising a 30 plurality of groups of crushing rods ar- ranged annularly about a common axis and fixed with respect one to another, the rods of said groups being free to move with re- spect one to another, but constantly assem- 35 bled en masse, means for rotating said groups in unison about said common axis, an anvil surface with which each group of rods co-acts, means for feeding material to be crushed to said groups midway of their 40 operative length within the operative sphere of said anvil and an annular series of pockets surrounding said groups of crushing rods adjacent their opposite ends and rotatable therewith for receiving a portion of the 45 crushed material for elevating the same and depositing it onto said rods.

In testimony whereof we have signed our names to this specification.

FREDERICK J. BEHNEMAN.
HAROLD S. REXWORTHY.
